(57) CLAIM

The ornamental design for a desk as shown and described.

DESCRIPTION

FIG. 1 is a front view of a first embodiment of the desk;
FIG. 2 is a back view of the desk shown in FIG. 1;
FIG. 3 is a left side view of the desk shown in FIG. 1;
FIG. 4 is a right side view of the desk shown in FIG. 1;
FIG. 5 is a top view of the desk shown in FIG. 1;
FIG. 6 is a bottom view of the desk shown in FIG. 1;
FIG. 7 is a front left top perspective view of the desk shown
in FIG. 1;
FIG. 8 is a front right top perspective view of the desk shown in FIG. 1; and
FIG. 9 is a back right bottom perspective view of the desk
shown in FIG. 1.
FIG. 10 is a front view of a second embodiment of the desk;
FIG. 11 is a back view of the desk shown in FIG. 10;
FIG. 12 is a left side view of the desk shown in FIG. 10;
FIG. 13 is a right side view of the desk shown in FIG. 10;
FIG. 14 is a top view of the desk shown in FIG. 10;
FIG. 15 is a bottom view of the desk shown in FIG. 10;
FIG. 16 is a front left top perspective view of the desk shown
in FIG. 10;
FIG. 17 is a front right top perspective view of the desk
shown in FIG. 10; and,
FIG. 18 is a back right bottom perspective view of the desk
shown in FIG. 10.
The broken lines depict parts of the desk that form no part of the claimed design.

1 Claim, 18 Drawing Sheets
